ELECTROCARDIAC DISPLAY UNIT

David P. Chuboff, North Barrington, and James P. Stevens, Chicago, Ill., assignors to Zenith Radio Corporation, Chicago, Ill., a corporation of Delaware

Filed Feb. 26, 1969, Ser. No. 15,916

Term of patent 14 years

Int. Cl. D24—02; D10—11
U.S. Cl. D83—1

The figure is a left side top and front perspective view of our design for an electrocardiographic display unit.

The right side (not shown) is the same as the left side shown, and the rear and bottom surfaces are plain and unornamented.

We claim:

The ornamental design for an electrocardiographic display unit, substantially as shown and described.
